United States Patent Office

Des. 181,763
Patented Dec. 17, 1957

181,763

PROJECTION HOUSING FOR A MICROFILM CAMERA OR SIMILAR ARTICLE

Robert Van Cleemput, Los Altos, Calif., assignor to
Dallas L. Cook, Palo Alto, Calif.

Application August 3, 1956, Serial No. 42,497

Term of patent 14 years

(Cl. D61—1)

Fig. 1 is a left-front perspective view of a projection housing for a microfilm camera or similar article, showing my new design, and

Fig. 2 is a right-front perspective view thereof.

The rear face of the housing is a plain, flat surface.

I claim:

The ornamental design for a projection housing for a microfilm camera or similar article, as shown and described.
